UNITED STATES PATENT OFFICE.

HENRY K. WOLFE, OF CHENEY, WASHINGTON, ASSIGNOR TO ROTARY ROD WEEDER & MFG. CO., INCORPORATED, OF CHENEY, WASHINGTON.

REVERSIBLE BEARING SHOE.

Application filed May 15, 1926. Serial No. 109,295.

The invention relates to rotary rod weeders of the type wherein a rod of polygonal cross section is moved forwardly and rotated beneath the surface of the soil to cut and macerate weeds, and the said invention generally resides in the provision of an improved construction of bearing shoe for that rotary rod and improved standards for mounting the same, the said shoe being so constructed and shaped as to be readily reversible to adapt the same either for acting to force the rod into hard soil or to tend to prevent too deep penetration thereof into very soft or sandy soil and the said mounting standards being constructed for so engaging the ground as to eliminate the making of furrows.

The invention further resides in the provision of a bearing shoe structure embodying features of great strength and durability, in which a readily replaceable thrust wear lug is provided, said lug being constructed and mounted in a manner rendering possible the ready removal and replacement thereof without removing the shoe from its secure relation upon the carrying standard end.

In its more specific nature the invention further resides in those novel details of construction, combination and arrangement of parts, all of which will be first fully described, then be particularly pointed out in the appended claims, reference being had to the accompanying drawings, in which:

Figure 1 is an end elevation of a rotary rod weeder with my invention operatively applied thereupon.

Figure 2 is a fragmentary end elevation showing the invention applied reversely to the illustration in Figure 1.

Figure 3 is a detail perspective view of the bearing shoe.

Figure 4 is a side elevation of the bearing shoe, the side opposite that illustrated in Figure 2 being shown.

Figure 5 is a horizontal section taken on the line 5—5 on Figure 4, a portion of a goose-neck type standard and a rod carrying bearing being shown in dotted line phantom.

Figure 6 is a diagrammatic cross section of a mounting standard and illustrates the manner in which the same may be drawn through the ground, either straight forward

or partially laterally without throwing up undesirable furrows.

Figure 7 is a view similar to Figure 5 and illustrates the manner in which the half bearing member or thrust lug may be removed without removing the shoe from its standard.

Figure 8 is a perspective view of a slightly modified form of shoe.

In the drawings, in which like numerals of reference indicate like parts in all of the figures, 1 indicates the framing of a rotary rod weeder structure, 2 the balancing plank thereof, 3 the supporting and traction wheels, 4 the power transmitting devices through which rotary motion is imparted to the rotary rod 5, which is of polygonal shape in cross section, and projects through and has bearing in the particular type of rod bearing which forms part of the subject matter of my present invention and is secured to the end of the peculiarly shaped supporting standards 6 also forming part of said invention.

In the use of rotary rod weeders of the types now generally employed farmers are meeting with much annoyance due to the throwing up of furrows by the standards of such weeders when drawn over and through the ground, which furrows collect water and form ditches. This necessitates the use of additional implements, following the weeding function, in order to leave the ground in the desired smooth state. Obviously this detracts greatly from the efficiency of rotary rod weeders and limits the extent and popularity of their use.

The types of weeders in general use are in the neighborhood of 12 feet in width and employ vertical standards of flat rectangular shape in cross section and which are mounted in a manner for presenting the edges thereof in the direction of travel of the weeders. It is very common, however, that when the weeders are drawn across a field one end or the other thereof will move in advance of the other causing the standards to engage the ground partially laterally, throwing up considerable furrows.

In my present invention I aim to overcome this fault by providing the goose-neck shaped and relatively narrow standards 6 which are of substantially ovate shape in cross section as will be seen by reference

to Figure 6 of the drawing. In this figure I have shown, between the thin full lines, the edge presented to the ground when the weeder is being dragged along perfectly straight; between the dot and dash lines, the edge presented to the ground when the weeder is travelling with the right end far in advance of the left; and, between the double dot and dash lines, the edge presented to the ground when the weeder is travelling with the left end thereof far in advance of the right. This diagram illustrates that in all three cases the obstructing area presented to the ground is the same.

By using such goose-neck ovate shaped standards, as the weeder is drawn over the ground, the earth thrown up by the standards will fall back into the furrows provided thereby and leave the ground quite smooth and level.

The detailed construction of the removable and reversible bearing shoe is illustrated in Figures 3, 4 and 5 of the drawing. The same includes a shank portion 7 having flanges 8 adapted to fit the end of the standard 6, which may be flattened if desired to facilitate such fit, and be secured thereto by suitable bolt and nut connections 9.

Each bearing includes a removable thrust 30 receiving half bearing member 10 having a shank 11 to lie in the cut-out 12 formed in the shank 7 flush with the same, and through which one of the bolt and nut connections 9 passes to serve as a securing means both for the shank 7 and the said member 10.

The shoulders 13 of the member 10 fit in the recesses 14 formed therefor in the shank 7, and the said member 10 includes a half bearing face 15 which opposes, in cooperative relation, the like shaped half bearing face 16 of the main shank 7.

The usual rotary rod carrying bearing member 17 is employed to ride in the bearing provided therefor by the opposing bearing surfaces 15 and 16 above referred to.

The bearing shoe shank is extended and shaped to provide a point 18 formed at the juncture of the edges 19 and 20.

It will be noticed that both edges 19 and 20 of the bearing shoe are extended in the same direction from the axis of the bearing, that is,—they both extend forwardly and downwardly (upwardly when reversed) from the axis, the edge 19 being more nearly horizontal than the edge 20 so that when the parts are positioned as shown in Figure 1, the bearing shoe will be adapted for use in hard soil, and by reason of its shape will tend to penetrate the ground as the weeder frame is pulled forwardly.

When used in sandy or soft soil where the rod will penetrate the ground with ease, the bearing shoe is reversed, as shown in Figure 2, and will then have a tendency to ride up out of the ground, thus preventing too deep

penetration of the rotary rod into the ground.

It will be observed by reference to Figures 3, 4 and 7 that the bearing surface 15 of the body 10 has the edges thereof at one side 70 curve cut as at 21, and the rear edge of the extended flange portion of that body is outwardly bevelled as at 22 for the purpose clearly illustrated in the said Figure 7.

The structural features just above mentioned serve to render possible the removal and replacement of a worn half bearing and thrust-lug member 10 without removing the shoe from its secure relation upon the lower end of a respective standard 6, it being possible by this equipment to remove and replace the said member by simply removing the foremost one of the securing bolts 9 which passes through the aperture with which the shank 11 of the member is provided.

By reference to Figure 7 of the drawings it will be observed that when it is desired to remove and replace one of the members 10 it is only necessary to remove the foremost bolt 9 above mentioned when the said member can, by reason of the bevelled edge and curved edge provisions 22 and 21 be canted and bodily removed in the manner indicated in full and dot lines in said figure 95 without disturbing the connection of the shoe member with the lower end of the bearing standard.

In Figure 8 of the drawings I have illustrated a slight modification of the bearing shoe in which the recesses 14 formed in the shoe shank terminate short of the upper and lower edges of the said shank thereby to provide upper and lower abutment shoulders 23, the shoulders 13 of the member 10 being suitably shortened to fit within the receiving recesses. In this manner the half bearing and thrust member is completely pocketed not only longitudinally but vertically also and unbroken upper and lower shank edges are presented for engagement with the ground, thus overcoming any tendency that might exist for weeds to work their way into the crevices that would surround the fully extended shoulders illustrated in Figure 3 of the drawings with the attendant tendency to loosen or shear the securing bolts.

In the foregoing description I have disclosed a simple and practical construction 120 of rotary rod bearing shoe which is readily reversible to adapt the same to efficient use either in soft, sandy, or hard soil and in which the thrust receiving member is rigidly held in proper relation and against displacement, but in a manner for being readily removable for replacement, thus permitting this important part, which is subjected to the greatest amount of wear, to be replaced when necessary without replacement of a 130

whole new bearing shoe and without the necessity of even removing the shoe from its standard. I have also disclosed a particularly efficient mounting standard for the shoe which permits draft of the weeder with a saving of power necessary to be applied and which makes possible the weeding action in a manner leaving the ground smooth and level.

From this description, it is thought that the novel details of construction, manner of application and the advantages of my invention will be readily apparent to those skilled in the art to which it relates.

What I claim is:

1. In rotary rod weeders, a goose-neck standard of substantially ovate cross section with the thicker portion thereof to the front, and a bearing shoe mounted on the lower end thereof.

2. In rotary rod weeders, a goose-neck standard of substantially ovate cross section with the thicker portion thereof to the front, a reversible bearing shoe, and means for securing the shoe to the lower end of the standard to cause the shoe to project therefrom and to be reversible thereupon without changing the direction of projection.

3. In combination with a bearing standard of a rotary rod weeder, a reversible bearing shoe, means for securing the bearing shoe to the standard to cause the shoe to project therefrom and to be reversible thereupon without changing the direction of projection.

4. In combination with a bearing standard of a rotary rod weeder, a reversible bearing shoe, means for securing the bearing shoe to the standard to cause the shoe to project therefrom and to be reversible thereupon without changing the direction of projection, the said shoe including edges converging to a point, one converging edge being more nearly in line with the direction of travel than the other such edges, that engagement of one such edge with the ground will urge penetration of the shoe into the ground when the shoe is secured in one position, and engagement of the other such edge with the ground will urge a lifting of the shoe toward the surface of the ground when the said shoe is secured in the reversed position.

5. In combination with a bearing standard of a rotary rod weeder, the rotary rod thereof, and a rod carrying bearing; a reversible bearing shoe including a shank having flanges adapted to fit over a part of the bearing standard, means for securing the shank to the standard to project therefrom substantially in the direction of travel of the weeder, the said shoe including edges converging to a point, one converging edge being more nearly in line with the direc-

tion of travel than the other such edge, that engagement of one such edge with the ground will urge penetration of the shoe into the ground when the shoe is secured in one position and engagement of the other such edge with the ground will urge a lifting of the shoe toward the surface of the ground when the said shoe is secured in the reversed position.

6. In combination with a bearing standard of a rotary rod weeder, the rotary rod thereof, and a rod carrying bearing; a reversible bearing shoe including a shank having flanges adapted to fit over a part of the bearing standard, a half bearing portion, so a cut-out portion between the flanges and merging with the half bearing portion, and shoulder receiving recesses in said flanges; a half bearing member having a shank to fit the cut-out portion, and shoulders adapted to fit in and engage said recesses to take up thrust exerted upon the rod carrying bearing rotatably mounted between the half bearing portion and the half bearing member; the said shoe shank and half bearing shank each having a cross aperture adapted to receive bolts for securing the whole structure reversibly upon the standard to project forwardly therefrom; the said shoe also including edges converging to a point, one converging edge being more nearly in line with the direction of travel than the other such edge that engagement of one such edge with the ground will urge penetration of the shoe into the ground when the shoe is secured in one position, and engagement of the other such edge with the ground will urge a lifting of the shoe toward the surface of the ground when the said shoe is secured in the reversed position.

7. A reversible bearing shoe including a shank adapted to be secured upon a carrying standard of a rotary rod weeder, a half bearing member removably mounted in the shoe and adapted to be secured with the shoe shank to the standard, means for securing the shank and half bearing member to the standard in a manner permitting removal of the half bearing member without disturbing the secure relation of the shank upon the standard.

8. A reversible bearing shoe including a shank adapted to be secured upon a carrying standard of a rotary rod weeder, a half bearing member removably mounted in the shoe and having a shank portion adapted to be secured with the shoe shank to the standard and a bevelled edge presented toward the standard upon which the shoe is mounted, and individual bolts for securing the shoe shank and the shank portion to the standard whereby and by reason of the bevel edge provision the said half bearing member may be individually released and removed without disturbing the mounting of the shoe.

9. A reversible bearing shoe including a shank having flanges adapted to fit over a part of the bearing standard, a half bearing portion, a cut-out portion between the flanges and merging with the half bearing portion, and shoulders receiving recesses in said flanges terminating short of the edges of the shoe to present unbroken edges of said shoe to engagement with the ground; a half bearing member having a shank to fit the cut-out portion, and shoulders adapted to fit in and engage said recesses to take up thrust exerted upon the rod carrying bearing rotatably mounted between the half bearing portion and the half bearing member; the said shoe shank and half bearing shank each hav-

ing a cross aperture adapted to receive bolts for securing the whole structure reversibly upon the standard to project forwardly therefrom; the said shoe also including edges converging to a point, one converging edge being more nearly in line with the direction of travel than the other such edge that engagement of one such edge with the ground will urge penetration of the shoe into the ground when the shoe is secured in one position, and engagement of the other such edge with the ground will urge a lifting of the shoe toward the surface of the ground when the said shoe is secured in the reversed position.

HENRY K. WOLFE.
